ARTICLE DISPENSING DEVICE

Peter Settecasi, New York, N. Y.

Application May 25, 1948, Serial No. 29,151

12 Claims. (Cl. 312—94)

1

This invention relates to article dispensing devices. It is particularly directed to a machine for vending candy and the like articles, in which the candy is stacked on a plurality of hinged shelves, one above the other in each chute, the arrangement being such that each time a pull bar is operated, the lowermost horizontal shelf drops down to vertical position to permit the candy or other article thereon to drop to dispensing position.

An object of this invention is to provide an article dispensing device of the character described, including a latch pivoted for rotation with each shelf, a fixed member engageable by all of the latches when the shelves are in horizontal position, a vertical slidable member and pawl means thereon to successively release the latches as said slidable member is reciprocated for successively dropping the shelves from the bottom upward in each chute.

Still another object of this invention is to provide in a device of the character described, means to prevent operation of the dispensing bar of each chute when said chute has been fully emptied.

Yet another object of this invention is to provide a strong, rugged and durable machine of the character described, which shall be relatively inexpensive to manufacture, easy to manipulate, which shall be sure and positive in operation and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims:

In the accompanying drawings in which is shown various illustrative embodiments of this invention,

Fig. 1 is a perspective view of a dispensing device embodying the invention;

Fig. 2 is a front elevational view thereof with parts broken away and in cross-section;

Fig. 3 is a side elevational view thereof with parts broken away and in cross-section;

Fig. 4 is a cross-sectional view, taken on line 4—4 of Fig. 3;

Fig. 5 is an enlarged partial view of the structure, shown in Fig. 4;

Fig. 6 is a view similar to Fig. 5 and showing

2

the lowermost latch released so that the shelf pivoted therewith has dropped;

Fig. 7 is a cross-sectional view taken on line 7—7 of Fig. 3;

Fig. 8 is a partial vertical view, illustrating the mechanism for lowering the sliding pawl carrier and showing the same in raised position;

Fig. 9 is a view similar to Fig. 8 but showing the pawl carrier being depressed;

Fig. 10 is a partial view showing one chute with the shelves in horizontal position and another chute with two shelves thereof down.

Referring now in detail to the drawing, 10 designates a vending or dispensing machine embodying the invention. The same comprises an outer casing having side walls 12, top wall 13, and front lower wall 14, a rearwardly extending horizontal wall 15 at the upper end of the front wall 14, and an upper front wall 16. At the bottom of wall 14 is a dispensing chamber 17.

Within the casing is a chute structure comprising a back wall 20 from which extends forwardly vertical partitions 21 dividing the structure into a plurality of vertical columns or chutes 22. Each partition 21 is formed with a front vertical flange 23. Extending through the back wall 20 and the flange 23 and journaled for rotation on each chute are a plurality of horizontal, vertically spaced shafts 24. Fixed to each shaft 24 for rotation therewith and disposed within chute 22 is a shelf 25. The shelves 25 may move from horizontal to vertical position. The shelves are spaced one above the other within each chute 22. The shelves extend across the chutes and articles to be vended are placed thereon. Means is provided for first dropping the lowermost shelf in any chute upon operating a dispensing mechanism for said chute. When said mechanism is again operated, the next higher shelf drops and so on until all the shelves have dropped in any chute. Thus, the candy is dropped first from the lowermost shelf and then from successively higher shelves, as will appear hereinafter. To this end, there is slidably mounted within said device and below each chute a horizontal bar 28. Attached to the forward end of each bar 28, by means of pin 28a is a draw bar 29, which is provided with a handle 30 at its forward end projecting through a suitable opening in front wall 14. Any suitable structure may be provided for supporting each bar 28 and its draw bar 29 for horizontal sliding movement forward and backward.

Attached to each draw bar 29 and extending downwardly therefrom is a hook 31. Journalled within the casing is a horizontal shaft 32.

Mounted on the ends of said shaft are a pair of links 33 interconnected by a horizontal shaft 34 parallel to shaft 32 and engaged by the hooks 31. Pivoted to one of the links 33 as at 33a is a link 35, which may be connected to any suitable coin controlled mechanism for locking shaft 34 against movement unless a proper coin is inserted into the machine. The bar 28 is formed in its upper edge adjacent its forward end with a notch or groove 36 for the purpose hereinafter appearing. Each bar 28 is furthermore formed at its rear end and at its upper side with a notch 37. The notch 37 has a front sharp shoulder 38 and a gradually inclined edge 39 extending therefrom. The edge 39 is inclined upwardly and rearwardly. Fixed to each bar 28 adjacent the rear upper end of inclined edge 39 is a pin 40, carrying a roller 41. It will be understood that when the proper coin is inserted into the machine, the handle 30 may be grasped and the draw bar 29 pulled forwardly and then released, suitable spring means being provided for retracting the draw bar.

As will be seen hereinafter, means is provided to cause a shelf to drop when the draw bar is retracted. To this end, there is fixed to the rear wall 20 a vertical guide member 43 aligned with each chute. Each member 43 is formed with a horizontal offset arm 44 at its upper end. Attached to said arm 44 is a shock absorber 45. Slidably mounted relative to each guide 43 is a vertical pawl carrier 47. Guide 43 may be provided with a headed pin 50 passing through a suitable slot 51 in wall 52 of the pawl carrier to serve as a guide for said carrier. The pawl carrier 47 may also be guided by a guide member 52a adjacent the lower end of each chute and also fixed to the back wall and carrying a headed pin 53 passing through slot 54 in wall 52 of said pawl carrier. Each pawl carrier 47 has a wall 55 parallel to the back wall 20. Pivoted to said wall are a plurality of vertically spaced pawls 56. Each pawl 56 is pivoted on a pivot pin 57 at its lower end. Each pawl furthermore has an offset flange 58 for the purposes hereinafter appearing.

Fixed to the back wall 20 and associated with each chute is a wall 60 formed with an offset flange 61. Wall 61 is formed with a plurality of vertical slots 62. There is one slot for each shaft 24 except the top shaft. Fixed to each shaft 24 and disposed rearwardly of wall 60 is a lever 65. Pivoted to each lever 65 as on pivot pin 66 is a latch member 67. Members 65 and 67 are formed with apertured ears 65a and 67a interconnected by coil tension spring 68. When any shelf is in horizontal position, its latch 67 passes through slot 62 and engages the lower edge of said slot for retaining the latch against disengagement with wall 61. The top latch engages the top edge of flange 61. Spring 68 normally biases members 65 and 67 together, but permits relative movement therebetween. When the pawl carrier 47 is in its up position contacting the shock absorber 45, the flanges 58 of pawls 56 contact their respective latches 67. Moreover, when said pawl carrier is in its up position, each flange 58 overlaps the latch 67 thereabove, but is restrained from engaging said latch by the latch associated therewith. However, should the pawl carrier be pulled down, the lowermost pawl will move to a position below the lowermost latch 67. When that happens, the lowermost pawl will drop by gravity to the position shown in Fig. 5 where it will be directly beneath the lowermost latch 67. When the pawl carrier is thereafter

raised, the lowermost pawl will engage the lowermost latch and rotate the same in a clockwise direction, looking at Fig. 5, to disengage said latch from wall 61, and due to the weight of the shelf 5 and particularly with a piece of candy or other article thereon, will cause the shelf to drop thereby moving latch 67 and its associated member 65 to the position shown in Fig. 6 where the shelf has dropped down to a vertical position causing the piece of candy or article thereon to drop down to the dispensing chamber.

Resilient means is provided for raising the pawl carrier 47 should said pawl carrier be depressed and then released. To this end, the pawl carrier 47 is interconnected to a fixed post on the chute by coil tension spring 70.

Means is provided to lower each pawl carrier each time the draw bar associated therewith is retracted after said draw bar has been pulled forwardly. To this end, there is fixed at the rear of wall 20 and adjacent its lower end and above the bars 28 a horizontal shaft 71. Hinged to shaft 71 and associated with each chute is a rocking member 72 having parallel flanges 73 and 74 and interconnected by wall 75 parallel to the shaft. Wall 75 is connected to the back wall by a coil compression spring 76 which tends to rotate said member in a counterclockwise direction looking at Fig. 3 of the drawing. On wall 75 is a roller 77 which overlies a foot 78 at the lower end of the pawl carrier 47. On said wall 73 is an offset finger 80, which projects down into notch 37. When the draw bar is pulled forwardly member 72 is rotated in a clockwise direction, looking at Fig. 3 of the drawing, from the full to the dotted line positions on Fig. 8. During such movement, spring 76 is tensioned and the bottom roller 77 is merely raised above the foot 78 of the pawl carrier 47, and said pawl carrier is unaffected. However, when the draw bar is retracted, roller 41 will engage the finger 80 and rotate member 72 in a counterclockwise direction, from the full line position of Fig. 8 to the position shown in Fig. 9, and roller 77 will depress the pawl carrier 47 and move the same from the position shown in Fig. 4 to the position shown in Fig. 5, permitting the lowermost pawl to drop below the lowermost latch. As soon as the roller 41 is past the finger in the retracting movement of the draw bar, spring 70 will raise the pawl carrier to cause the lowermost pawl 56 to release the lowermost latch 67 so that it moves from position shown in Fig. 5 to the position shown in Fig. 6, whereby the lowermost shelf in this chute drops, and the candy piece or article thereon falls down to the dispensing chamber. When the draw bar is again reciprocated, next to the lowest pawl will drop below next to the lowest latch, then as the pawl carrier again lifts next to the lowest latch is disengaged from wall 61, so that next to the lowest shelf drops by gravity. When the action is repeated, the shelves in each chute operated drop successively from the bottom upward.

Means is provided to lock each draw bar against movement when all of the shelves in said chute have dropped, to a vertical position. To this end, there is pivoted to a front wall 90 at the lower end of each chute, as on pivot 91, a member 92 formed with a finger 93 aligned with the notch or groove 36 on bar 28 for said chute. Means is provided to retain member 92 in raised position while the topmost shelf in the chute is in horizontal position so that the finger 93 will not enter notch 36. To this end, each mem-

ber 92 is formed with an offset finger 95. Connected to finger 95 is one end 36 of a wire rod 97 which extends upwardly within the chute and has at its upper end, an offset finger 98 engaging the topmost shelf 25. While the topmost shelf 25 is in raised or horizontal position, it retains member 92 in raised position. However, when the topmost shelf drops, member 97 will drop and member 92 will rotate about pivot 94 so that the finger 93 enters notch 36 to prevent the draw bar associated with that particular chute from being further operable.

After all the shelves in a chute have dropped, they can be raised successively from the bottom upwardly and as each shelf is raised, its latch will engage wall 61. When all the shelves have been raised, all of the latches will be in engagement with wall 61 and the shelves will remain in horizontal position, until further dropped in a manner hereinbefore explained.

While the mechanism has been explained for one chute 22, it will be understood that the mechanism is the same for each chute for controlling the shelves.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings, is to be interpreted as illustrative and not in a limiting sense.

Having thus described my invention, I claim as new and desire to protect by Letters Patent:

1. In an article dispensing device, a chute, a plurality of vertically spaced shelves pivoted about horizontal, vertically aligned parallel axles, a latch associated with each axle, a fixed wall having portions engageable by said latches, a vertically slidable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotal movement when the pawl carrier is depressed, and said lowermost pawl being adapted to rotate to a position below its latch when said pawl carrier is depressed and said lowermost pawl being adapted to disengage its latch when said pawl carrier is raised after being depressed, to allow the lowermost shelf to drop, and whereby each time the pawl carrier is again depressed and raised, the next higher latch will be disengaged and the shelf associated therewith will drop.

2. In an article dispensing device, a chute, a plurality of vertically spaced shelves pivoted about horizontal, vertically aligned parallel axles, a latch associated with each axle, a fixed wall having portions engageable by said latches, a vertically slidable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotal movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, means to

each pawl being adapted to move below the lower end of its latch when the pawl carrier is depressed, each pawl above the lowermost pawl being engaged by the latch below the latch associated therewith and being retained thereby against pivotal movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, and means to cause said pawl carrier to be depressed and raised each time said draw bar is reciprocated.

3. In an article dispensing device, a chute, a plurality of vertically spaced shelves pivoted about horizontal, vertically aligned parallel axles, a latch associated with each axle, a fixed wall having portions engageable by said latches, a vertically slidable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotal movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, means to cause said pawl carrier to be depressed and raised each time said draw bar is reciprocated, and means to prevent movement of the draw bar when the topmost shelf drops.

4. In an article dispensing device, a chute, a plurality of vertically spaced shelves pivoted about horizontal, vertically aligned parallel axles, a latch associated with each axle, a fixed wall having portions engageable by said latches, a vertically slidable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotal movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, means to

cause said pawl carrier to be depressed and raised each time said draw bar is reciprocated, and means to prevent movement of the draw bar when the topmost shelf drops, each latch comprising a member fixed for rotation with the shelf, a member pivoted to the first member, and a spring interconnecting said members.

5. In a dispensing device, a plurality of parallel horizontal axles disposed in a common vertical plane, a shelf fixed to each axle for rotation therewith, a lever fixed to each axle for rotation therewith, a latch pivoted to each lever about a pivot parallel to and spaced from its axle, spring tension means interconnecting each lever with its latch to normally cause each latch to rotate in one direction relative to its lever, a vertical fixed wall formed with edge portions engageable by said latches, a vertical pawl carrier mounted for vertical sliding movement, a plurality of pawls pivoted to said pawl carrier, there being one pawl for each latch, an upper end of each pawl normally overlapping its latch, and each pawl being engageable by the latch below the latch associated therewith, spring means to raise the pawl carrier, and means to lower the pawl carrier to a point where the upper end of each pawl is below the lower end of its latch.

6. In a dispensing device, a plurality of parallel horizontal axles disposed in a common vertical plane, a shelf fixed to each axle for rotation therewith, a lever fixed to each axle for rotation therewith, a latch pivoted to each lever about a pivot parallel to and spaced from its axle, spring tension means interconnecting each lever with its latch to normally cause each latch to rotate in one direction relative to its lever, a vertical fixed wall formed with edge portions engageable by said latches, a vertical pawl carrier mounted for vertical sliding movement, a plurality of pawls pivoted to said pawl carrier, there being one pawl for each latch, an upper end of each pawl normally overlapping its latch, and each pawl being engageable by the latch below the latch associated therewith, spring means to raise the pawl carrier and means to lower the pawl carrier to a point where the upper end of each pawl is below the lower end of its latch, said means comprising a sliding draw bar, a bell crank pivoted about a horizontal axis and having an arm engaging a foot on the pawl carrier, a draw bar having means to engage another arm of the bell crank for rotating the bell crank when the draw bar is pulled in one direction for moving the arm which engages the foot on the pawl carrier away from the pawl carrier and said draw bar being adapted to rotate the bell crank in an opposite direction when the draw bar is retracted to cause the arm which engages the foot on the pawl carrier to depress the pawl carrier.

7. In a dispensing device, a plurality of parallel horizontal axles disposed in a common vertical plane, a shelf fixed to each axle for rotation therewith, a lever fixed to each axle for rotation therewith, a latch pivoted to each lever about a pivot parallel to and spaced from its axle, spring tension means interconnecting each lever with its latch to normally cause each latch to rotate in one direction relative to its lever, a vertical fixed wall formed with edge portions engageable by said latches, a vertical pawl carrier mounted for vertical sliding movement, a plurality of pawls pivoted to said pawl carrier, there being one pawl for each latch, an upper end of each pawl normally overlapping its latch, and each pawl being engageable by the latch below the latch associated

therewith, spring means to raise the pawl carrier and means to lower the pawl carrier to a point where the upper end of each pawl is below the lower end of its latch, said means comprising a sliding draw bar, a bell crank pivoted about a horizontal axis and having an arm engaging a foot on the pawl carrier, a draw bar having means to engage another arm of the bell crank for rotating the bell crank when the draw bar is pulled in one direction for moving the arm which engages the foot on the pawl carrier away from the pawl carrier and said draw bar being adapted to rotate the bell crank in an opposite direction when the draw bar is retracted to cause the arm which engages the foot on the pawl carrier to depress the pawl carrier, and spring means for rotating said bell crank in a direction for retaining its first arm in engagement with said foot of said pawl carrier.

8. In a dispensing device, a plurality of parallel horizontal axles disposed in a common vertical plane, a shelf fixed to each axle for rotation therewith, a lever fixed to each axle for rotation therewith, a latch pivoted to each lever about a pivot parallel to and spaced from its axle, spring tension means interconnecting each lever with its latch to normally cause each latch to rotate in one direction relative to its lever, a vertical fixed wall formed with edge portions engageable by said latches, a vertical pawl carrier mounted for vertical sliding movement, a plurality of pawls pivoted to said pawl carrier, there being one pawl for each latch, an upper end of each pawl normally overlapping its latch, and each pawl being engageable by the latch below the latch associated therewith, spring means to raise the pawl carrier and means to lower the pawl carrier to a point where the upper end of each pawl is below the lower end of its latch, said means comprising a sliding draw bar, a bell crank pivoted about a horizontal axis and having an arm engaging a foot on the pawl carrier, a draw bar having means to engage another arm of the bell crank for rotating the bell crank when the draw bar is pulled in one direction for moving the arm which engages the foot on the pawl carrier away from the pawl carrier and said draw bar being adapted to rotate the bell crank in an opposite direction when the draw bar is retracted to cause the arm which engages the foot on the pawl carrier to depress the pawl carrier, and means controlled by the topmost shelf to retain the draw bar against movement.

9. In a dispensing device, a plurality of parallel horizontal axles disposed in a common vertical plane, a shelf fixed to each axle for rotation therewith, a lever fixed to each axle for rotation therewith, a latch pivoted to each lever about a pivot parallel to and spaced from its axle, spring tension means interconnecting each lever with its latch to normally cause each latch to rotate in one direction relative to its lever, a vertical fixed wall formed with edge portions engageable by said latches, a vertical pawl carrier mounted for vertical sliding movement, a plurality of pawls pivoted to said pawl carrier, there being one pawl for each latch, an upper end of each pawl normally overlapping its latch, and each pawl being engageable by the latch below the latch associated therewith, spring means to raise the pawl carrier and means to lower the pawl carrier to a point where the upper end of each pawl is below the lower end of its latch, said means comprising a sliding draw bar, a bell crank pivoted about a horizontal axis and having an arm engaging a foot on the pawl carrier,

draw bar having means to engage another arm of the bell crank for rotating the bell crank when the draw bar is pulled in one direction for moving the arm which engages the foot on the pawl carrier away from the pawl carrier and said draw bar being adapted to rotate the bell crank in an opposite direction when the draw bar is retracted to cause the arm which engages the foot on the pawl carrier to depress the pawl carrier, and means controlled by the topmost shelf to retain the draw bar against movement, said movement comprising a pivoted member, means associated with the topmost shelf to normally raise the pivoted member and permitting said pivoted member to engage a notch in the draw bar when the topmost shelf drops.

10. In an article dispensing device, a chute, a plurality of vertically spaced shelves pivoted about horizontal, vertically aligned parallel axles, a latch associated with each axle, a fixed wall having portions engageable by said latches, a vertically slideable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotable movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, and means to cause said pawl carrier to be depressed and raised each time said draw bar is reciprocated, said means comprising a pivoted member having an arm disposed over a foot on the pawl carrier, means to raise said arm above the foot when the draw bar is pulled, and means to depress said arm when said draw bar is retracted so that said arm will depress said foot and said pawl carrier.

11. In an article dispensing device, a chute, a plurality of vertically spaced shelves pivoted about horizontal, vertically aligned parallel axles, a latch associated with each axle, a fixed wall having portions engageable by said latches, a vertically slideable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotable movement when the pawl carrier is depressed, and said lowermost pawl being adapted to ro-

tate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop a reciprocable draw bar, and means to cause said pawl carrier to be depressed and raised each time said draw bar is reciprocated, said means comprising a pivoted member having an arm disposed over a foot on the pawl carrier, means to raise said arm above the foot when the draw bar is pulled, and means to depress said arm when said draw bar is retracted so that said arm will depress said foot and said pawl carrier, and spring means to raise said pawl carrier.

12. In an article dispensing device, a chute, a plurality of vertically spaced shelves pivoted about horizontal, vertically aligned parallel axles, a latch associated with each axle, a fixed wall having portions engageable by said latches, a vertically slideable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotable movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, and means to cause said pawl carrier to be depressed and raised each time said draw bar is reciprocated, said means comprising a pivoted member having an arm disposed over a foot on the pawl carrier, means to raise said arm above the foot when the draw bar is pulled, and means to depress said arm when said draw bar is retracted so that said arm will depress said foot and said pawl carrier, and spring means to raise said pawl carrier.

13. In an article dispensing device, a chute, a plurality of vertically spaced shelves pivoted about horizontal, vertically aligned parallel axles, a latch associated with each axle, a fixed wall having portions engageable by said latches, a vertically slideable pawl carrier, a plurality of pawls pivoted to said pawl carrier, there being a pawl associated with each latch, the upper end of each pawl overlapping the lower end of the latch associated therewith when the pawl carrier is in its raised position, and the upper end of each pawl being adapted to move below the lower end of its latch when the pawl carrier is depressed, each pawl above the lowermost pawl being engaged by the latch below the latch associated therewith and being retained thereby against pivotable movement when the pawl carrier is depressed, and said lowermost pawl being adapted to rotate to a position below its latch when said pawl carrier is depressed and said lowermost pawl being adapted to disengage its latch when said pawl is raised after being depressed, to allow the lowermost shelf to drop, and whereby each time the pawl carrier is again depressed and raised, the next higher latch will be disengaged and the shelf associated therewith will drop, a reciprocable draw bar, and means to cause said pawl carrier to be depressed and raised each time said draw bar is reciprocated, said means comprising a pivoted member having an arm disposed over a foot on the pawl carrier, means to raise said arm above the foot when the draw bar is pulled, and means to depress said arm when said draw bar is retracted so that said arm will depress said foot and said pawl carrier, and spring means to raise said pawl carrier.

PETER SETTECASI.
